UNITED STATES PATENT OFFICE.

JOHN REIMANN, JR., OF TIBBEE STATION, MISSISSIPPI.

RAIL-JOINT.

1,088,625.

Specification of Letters Patent.

Patented Feb. 24, 1914.

Application filed May 23, 1913. Serial No. 769,474.

To all whom it may concern:

Be it known that I, JOHN REIMANN, Jr., a citizen of the United States, residing at Tibbee Station, in the county of Clay and State of Mississippi, have invented new and useful Improvements in Rail-Joints, of which the following is a specification.

The present invention relates to improvements in rail joints.

10 In carrying out my invention it is my purpose to so construct the ends of two railway rails that, when connected, the same will provide a joint which will prevent the downward movement of the rails at the joint, the 15 lateral movement of the said joint and permit of only a limited longitudinal movement.

A further object of the invention is the provision of a rail joint wherein the employment of fish plates, rail chair and the 20 like is dispensed with, and further wherein the bolts connecting the joint will be effectively sustained against accidental removal.

It is a still further object of the invention to construct one end of a rail in such a manner as to effectively support the end of a 25 second rail end, the said second rail having its end of the ordinary construction, but having its base flange cut and its web at its head provided with lugs which are welded 30 or otherwise secured thereto, the extending web of the said rail adapted to be received within a suitable channel provided in the end of the first mentioned rail, and the lugs of the 35 said second rail being received in depressions provided in the walls of the channels of the said first mentioned rail.

With the above recited objects in view, and others which will appear as the nature of the invention is more fully understood, 40 the improvement resides in the construction, combination and arrangement of parts set forth in the following specification and falling within the scope of the appended claims.

In the drawings: Figure 1 is a side elevation of a rail joint constructed in accordance with my invention, Fig. 2 is a section on the line 2-2 of Fig. 1, Fig. 3 is a horizontal sectional view taken approximately on the line 3-3 of Fig. 1, Fig. 4 is a transverse sectional view on the line 4-4 of Fig. 1, Fig. 5 is a perspective view of one rail end, Fig. 6

is a similar view of the second rail end, Fig. 7 is a detail perspective view of the nut lock, Fig. 8 is a central vertical longitudinal sectional view through the device, and Fig. 9 55 is a view of an ordinary rail end, or the end of a broken rail having its base flange cut and provided with welded lugs which are adapted to be received within one of the rail end sections of my improved joint. 60

Referring now to the drawings in detail, R—R' designate the rails. The rail R is formed with an enlarged end and a base which extends a suitable distance beyond the terminal of its head. The sides of the enlarged end are arranged approximately in the same vertical plane as are the sides of the head of the rail. The enlarged extension is centrally longitudinally channeled, as at 1, and the walls 2 and 3 provided by the said channel, adjacent the terminal of the enlarged portion are each provided with registering notches 4. The channel extends a suitable distance beneath the terminal of the head to provide the end of the said channel 75 with what I will term a pocket 5. The second rail R' is of the ordinary construction, except that the said rail has its base flange cut away for a suitable distance from the end of its web, to provide the said flange 80 with a shoulder 6, and the head terminates at 7, while the web projects a suitable distance beyond the said end 7. The lower wall or edge of the projecting portion of the web is rounded, as indicated by the numeral 8, 85 and integrally formed upon the web, a slight distance beyond the shoulder 6, and arranged at the juncture of the web and head of the said rail, are oppositely disposed lugs 9. These lugs have their lower, and what may 90 be termed their inner corners rounded, as at 10. By arranging the end of the rail R' at an angle with relation to the rail R and inserting its extending web within the channel 1 of the rail R so that the end 7 of its head 95 contacts with the end of the head of the rail R, the lugs 9 will be disposed directly above the notches 4 of the walls 2 and 3 of the rails R, and a further downward pressure upon the rail R' will bring the said lugs into 100 the notches, the extension of the web of the rail R' being also positioned within the

pocket, and the upper edge of the same contacts with the upper wall of the pocket, while the head of the rail R' at the opposite sides of its web extension rests upon the 5 upper edge of the walls 2 and 3.

The web extension of the rail R' is provided with openings which register with similar openings in the walls 2 and 3, the alining openings being adapted for the 10 reception of bolts 11 having the usual securing nuts 12.

The numeral 13 designates a plate which is provided with openings and which is adapted to serve a double purpose of a 15 washer plate which is adapted to be arranged between one of the walls 2 or 3, and the nuts 12, as well as to provide a hinged connection for a nut lock plate 14. The plate 14 is adapted to be swung between the 20 oppositely disposed nuts 12 when the nuts are screwed entirely home upon the bolts, and to contact with the sides of the said nuts to prevent the accidental rotation of the nuts upon the bolts. The bolts, adjacent 25 their heads are rectangular, and certain of the openings in either the walls 2 or 3 are likewise of a rectangular formation, so that the accidental rotation of the bolts is thus effectively prevented.

30 The rail R may be employed in connection with the end of an ordinary rail which is illustrated in Fig. 9 of the drawing and which is designated by the numeral 15. The rail has its web and head cut vertically and 35 transversely and its web, at its juncture with its base flange, cut longitudinally a suitable distance from the end of the web and head, and the base flange cut transversely, so that the web may be received within the channel 40 1 of the rail R and have the end of its base flange contact with the end of the base flange of the said rail R. The rail 15 has welded thereon, or is otherwise provided with lugs 16, the said lugs being arranged at the junction 45 of the web and head of the rail 15 beyond the end of its base, and the said lugs 16 are adapted to be received within the notches 4 provided by the walls 2 and 3 of the rail R when the rail end 15 is arranged 50 within the rail end R. In other respects, the device is similar to that described, being provided with the securing nuts and bolts and the wear plate 13 having the hinged lock plate 14.

55 From the above description taken in connection with the accompanying drawings, the simplicity of the device as well as the advantages therof will, it is thought, be perfectly apparent to those skilled in the

art to which such inventions appertain with- 60 out further detailed description.

Having thus described the invention, what I claim as new is:

1. In a rail joint, two rails having co-acting ends, the web of one of said rail ends being enlarged and being extended beyond its head, the enlargement being centrally channeled to provide opposite walls, said walls having registering notches the outer faces of which are disposed flush with 70 the sides of the head of the rail, the channel extending beneath the head to provide a pocket, the second rail end having a web extension and a head extension, the web extension projecting beyond the end of the 75 head extension, the end of the head extension being beveled, the said web extension being formed beneath its head and upon its opposite faces with lugs, the lower and inner corners of which being rounded, 80 the portion of the web extension beyond the end of the head having its lower edge rounded, the said web extension adapted to be arranged within the channel of the first mentioned rail to have the projecting portion of its web received within the pocket of the channel, its lugs received within the notches of the side walls of the channel, and means, comprising nuts and bolts, for securing 85 the rail ends. 90

2. In a rail joint, two co-acting rails, one of said rails having its end enlarged and centrally formed with a channel, the side walls provided by the channel being notched, the said side walls being provided with non-circular bolt receiving openings, the second rail having a head and web extension, and being provided with bolt openings, the said second rail having secured beneath its head and to its web extension oppositely disposed 100 lugs, the extension adapted to be received within the channel and its lugs arranged within the notches of the first mentioned rail, bolts having rectangular portions adjacent their heads engaging the non-circular openings in one of the plates and passing through the remaining registering openings, a bearing plate arranged upon the bolts and contacting with one of the side walls of the channelled rail joint, and nuts for the 105 bolts. 110

In testimony whereof I affix my signature in presence of two witnesses.

JOHN REIMANN, JR.
